UNITED STATES PATENT OFFICE.

DAVID S. HITCHCOCK, OF CLEVELAND, OHIO.

BOTTLE-STOPPER.

SPECIFICATION forming part of Letters Patent No. 361,285, dated April 19, 1887.

Application filed February 25, 1887. Serial No. 228,908. (No model.)

To all whom it may concern:

Be it known that I, DAVID S. HITCHCOCK, of the city of Cleveland, county of Cuyahoga, State of Ohio, have invented a new and useful Improvement in Bottle-Stoppers, of which the following is a specification.

My invention relates to stoppers for tightly closing the mouths of bottles containing aerated or other liquids, and especially to the stopper, which is permanently attached to the neck of the bottle by a device which serves to compress the stopper into and to draw it out of the mouth of the bottle; and the object of my improvement is to provide a practical mechanism for compressing and withdrawing the stopper, and for permanently attaching the same to the bottle. I attain this object by the mechanism illustrated in the accompanying drawings, in which similar letters refer to similar parts throughout the several views.

Figures 1 and 4 are side elevations showing my improvement applied to the neck, head, and mouth of a bottle. Fig. 2 is a front elevation of the same. Fig. 3 is a rear elevation 25 of the same. Fig. 5 is a side elevation showing my improved device or mechanism detached from the bottle.

To enable others skilled in the art to make and use my invention, I herewith describe its 30 construction and operation.

A designates the head of the bottle, and D the neck of the bottle.

B designates the bail which serves to connect the device to the bottle, this bail being 35 made of thick wire bent in an approximately U shape, and turned inwardly at its ends to form pivots, as shown at h h, its upper part being contracted in such manner as to form a short straight section, as shown at X', around 40 which the upper end of the lever L is attached or coiled. A smaller wire, m, encircles the neck of the bottle under the head A at and near where it is joined to the neck, and is coiled around the ends h h of the bail B, as 45 at n n, to pivotally connect the bail to the neck of the bottle, and the ends of said wire are twisted or otherwise fastened at K, so as to securely hold the bail in position.

The stopper C may be constructed in any 50 suitable form of a rubber or other elastic washer or gasket, e, surrounding or attached to a solid or rigid central portion, C, sur-

mounted by a flat disk-shaped head, d. Upon the head of d is formed a lug, e, having an opening or orifice, for the purpose hereinafter 55 specified.

L designates the lever or handle for operating the device. This lever is formed of a flat stiff piece of metal of suitable length, and bent outwardly at X³, contiguous to its end X⁴, so as to form a thumb-piece, by which the required upward and downward pressure is applied to the lever. The lever is also bent at X⁵, so as to pass over the top of the stopper and under the bail B, and its upper end 65 is bent or coiled around the straight top section of the bail, as at X', securing the lever to the bail in such way as to allow the lever to turn freely on the bail. Attached to the lever L at or near the point B, by a rivet or other 70 suitable device, is a spring, S, made of a flat piece of stiff steel or other suitable material, and extending over and bent or coiled through the orifice of the lug e, securing it to the lug in such a way as to allow it to turn freely on 75 the lug. The lever is attached to the bail and the spring to the lug in such manner that when the lever is depressed the bail is carried past the center on the lever side, so that the stopper is tightly pressed into the mouth of 80 the bottle, and the spring exerts such pressure on the stopper that the stopper always—and especially when by use or otherwise the elastic washer has lost any of its elasticity—is kept tightly pressed into the mouth of the 85 bottle.

The lever L may be constructed of a flat stiff piece of metal of suitable length to allow it to be bent upon itself at a point about midway of its length, as shown in Fig. 1, the lower 90 or under side of which, when riveted or otherwise fastened at B and its end bent or coiled on the lug, as above described, shall form the spring S.

Having thus described my invention, what 95 I claim as new, and desire to secure by Letters Patent, is—

1. In a bottle-stopper, the combination, with the bail and stopper, of the bent lever secured to the bail, and the spring riveted or otherwise 100 secured to the lever and coiled over and through the lug on the stopper, all constructed and operated substantially as shown.

2. The combination, with the bottle having

a head, A, and neck D, and a wire bail, B, with its ends bent as shown at $h\ h$, of a wire, m , a stopper, constructed substantially as described, having a lug with one orifice, a lever, 5 L, composed of a flat stiff piece of metal, having the bends $X' X^2 X^3 X^4$, and a spring, S, composed of a flat piece of stiff metal, riveted or otherwise secured to the lever and coiled over and through the lug, substantially as and for the purposes shown and described.

DAVID S. HITCHCOCK.
